UNITED STATES PATENT OFFICE.

ANDREW J. ENGLISH, OF CINCINNATI, OHIO.

HYDROCARBON-BURNER.

SPECIFICATION forming part of Letters Patent No. 443,509, dated December 30, 1890.

Application filed July 15, 1889. Serial No. 317,638. (No model.)

To all whom it may concern:

Be it known that I, ANDREW J. ENGLISH, a citizen of the United States, residing at Cincinnati, Ohio, have invented new and useful

5 Improvements in Hydrocarbon-Burners, of which the following is a specification.

My invention relates to hydrocarbon-vaporizing burners in which gasoline or other volatile hydrocarbon is employed and first "vaporized" by the heat of the burner engendered by the ultimate flame. The common mode of "starting" such burners in operation is to unscrew the "needle-valve" and allow the liquid gasoline to flow down into an open 15 shallow receptacle or cup arranged beneath the burner and its retort, where it is ignited, and by the heat of the flame thus produced the retort is sufficiently heated to begin operations. This, however, besides being some- 20 what dangerous by reason of the liability to overflow the cup and cause the burning gasoline to drop downward upon the floor beneath, also involves an excessive wear and sometimes breakage of the needle-valve, 25 which, having been closed at the conclusion of a previous use of the burner while yet the parts were hot and expanded, becomes firmly set and wedged in position by the subsequent cooling and contraction of the parts. The 30 latter difficulty is one inherent in the ordinary construction and use of such burners, while that first named is a more or less serious danger, according to the skill or want of skill of the attendant.

35 The object of my invention is to obviate both these difficulties and furnish a means of heating the burner, as a preliminary to its general operation, at once simple, effective, requiring no skill on the part of the operator, 40 and requiring no unseating of the needle-valve until the parts are warm and restored to that condition of expansion in which the needle-valve was closed.

To this end my invention consists in combining with a vaporizing hydrocarbon-burner a detachable heating-cartridge of suitable absorbent material and a bracket or holding device adapted to hold the detachable cartridge in proper heating relation to the burner, 45 which cartridge, being saturated with an inflammable liquid—such as alcohol, gasoline,

&c.—and placed in proper position relatively to the burner and retort and lighted, furnishes the heat necessary to start the burner in operation.

55

Mechanism embodying my invention is illustrated in the accompanying drawings, in which—

Figure 1 is a side elevation of an ordinary hydrocarbon-heating burner with its detachable heating-cartridge held in proper relation to the same by a bracket-arm formed as an attachment to the burner; Fig. 2, a plan view of the same. Fig. 3 is a perspective view of the cartridge detached.

65

Figure 1 is a side elevation of an ordinary hydrocarbon-heating burner with its detachable heating-cartridge held in proper relation to the same by a bracket-arm formed as an attachment to the burner; Fig. 2, a plan view of the same. Fig. 3 is a perspective view of the cartridge detached.

Referring now to the drawings, A designates the ordinary heating-burner of a gasoline or "vapor" stove, which, being of a form now commonly in use, will require no special description, it being sufficient to say that the gasoline ascending through the pipe a and through the passage b, (indicated by dotted lines in Fig. 2,) which practically constitutes the retort, is discharged as a vapor, and as controlled by the needle-valve c into the throat d of what is commonly termed the "mixing-chamber" e of the burner, whence it issues radially outward through the interstices of the corrugated plates f, the heat of combustion serving to keep the parts, and particularly the retort, at the proper temperature for continued operation.

65

In the present illustration of my invention I have shown a bracket-arm B attached to or formed as part of the casing c' of the needle-valve c. This arm is suitably bent to form a holding-shelf, upon which an absorbent heating-cartridge C is adapted to rest in proper position beneath the burner and its retort. The cartridge itself is conveniently constructed as a cylinder of wire-gauze or perforated sheet metal and filled with a suitable absorbent earth—such, for example, as tripoli, (a diatomaceous earth)—or with asbestos, or, indeed, any refractory and absorbent material. The cartridge is provided with a suitable handle h, and is charged by being immersed in an inflammable liquid and allowed to remain until saturated partially or wholly therewith.

70

The mode of operation is sufficiently obvious. The saturated cartridge, being placed

75

90

95

100

upon its supporting-shelf, is ignited with a match or otherwise, and its flame communicates the desired heat to the burner and its attachments and may be removed when its 5 office is performed.

While I have herein shown and described a permanent shelf or bracket attachment to the burner as a means of supporting the cartridge, yet it will be obvious that it may be 10 supported in a variety of ways or by a supporting-shelf arranged in any other manner. Neither is the precise form of construction of the cartridge material, as any combined mass 15 of porous material capable of absorbing the inflammable liquid for the use indicated may be employed.

I claim as my invention and desire to secure by Letters Patent of the United States—

1. The combination, with a vaporizing hy-

drocarbon-burner and a detachable absorbent 20 heating-cartridge, of a bracket or holding device adapted to hold the detachable cartridge in proper heating relation to the burner, substantially as described.

2. The combination, with a vaporizing hydrocarbon-burner, of a bracket-arm projecting from said burner and a detachable heating-cartridge supported on said bracket-arm beneath the burner, substantially as described. 25

In testimony whereof I have hereunto set my hand in the presence of two subscribing witnesses. 30

ANDREW J. ENGLISH.
